J. WINN & A. FEINBERG,
SAFETY LOCK,
APPLICATION FILED MAY 26, 1914.

1,175,394.

Patented Mar. 14, 1916.

UNITED STATES PATENT OFFICE.

JOHN WINN, OF BROOKLINE, AND AARON FEINBERG, OF DORCHESTER, MASSACHUSETTS.

SAFETY-LOCK.

1,175,394.

Specification of Letters Patent. Patented Mar. 14, 1916.

Application filed May 26, 1914. Serial No. 840,975.

To all whom it may concern:

Be it known that we, JOHN WINN, a citizen of the United States, and a resident of Brookline, county of Norfolk, Commonwealth of Massachusetts, and AARON FEINBERG, a citizen of the United States, and a resident of Dorchester, county of Suffolk, Commonwealth of Massachusetts, have invented certain new and useful Improvements 10 in Safety-Locks, of which the following is a specification accompanied by drawings.

This invention relates to safety locks, but more particularly to safety tongues or bolts for spring-latch locks, independent of the 15 manner in which the locks are normally operated or opened. In a spring-latch lock of almost any usual construction, having a slidable bolt provided with a beveled end, it is generally possible to force the lock by 20 inserting a piece of thin flexible material as celluloid or thin sheet metal between the door and door-jamb, and against the beveled end of the bolt, thus forcing the bolt out of the lock strike, and permitting the door 25 to be opened. There is usually more or less space or clearance between the edge of the door and the door jamb, protected to some degree by molding or a rabbet, but no great obstacle is ordinarily afforded 30 against the insertion of such a piece of material as described.

The primary object of this invention is to provide an improved construction of 35 tongue or bolt and coöperating parts in the lock casing and lock strike, which will permit the bolt to freely enter the strike and be freely withdrawn therefrom by the lock mechanism of any suitable character, but the bolt cannot be forced by the insertion 40 of a piece of thin flexible material between the door and door jamb. To these ends the bolt is provided with a safety catch or projection at its beveled end which catches on the strike in case the lock is attempted to 45 be forced in the manner described.

The invention is shown in its preferred forms in the accompanying drawings, in which—

Figure 1 is a longitudinal sectional view 50 partly broken away of one form of the invention; Fig. 2 is a detail plan view partly in horizontal section and partly broken away; Fig. 3 is a transverse sectional view of Fig. 2 on the line 3—3 looking in the direction of the arrows; Fig. 4 is a longitudi-

nal sectional view of a modification of the invention; Fig. 5 is a detail plan view of Fig. 4, partly in horizontal section and partly broken away; and Fig. 6 is a transverse sectional view of Fig. 5 on the line 60 6—6 looking in the direction of the arrows.

Referring to the drawings, and more especially to the form of the invention shown in Figs. 1, 2 and 3, A represents a suitable lock casing adapted to be secured to the door B 65 as by means of the usual plate C, and D represents the lock strike adapted to be secured to the door jamb E. For the purposes of this invention, the cavity F behind the strike D should be undercut to permit the 70 head of the bolt to enter.

The slidable tongue or bolt G is provided at one end H with suitable means adapted to coöperate with the lock mechanism which may be provided with a spring (not 75 shown). The head J of the bolt has a beveled face K and a locking toe or projection L forms a continuation of the face K. The upper surface of this projection L is curved at O and is otherwise substantially parallel 80 to the beveled face K, so that the surfaces K and O have the same slope and bear substantially the same angular relation to the plane of the lock strike D. The ends of the projection L are connected to the body of the 85 head J by means of the webs P, which incline backwardly and form cam surfaces which coöperate with the strike D as the bolt is withdrawn by the lock mechanism. The inner end of the bolt H is guided in the 90 ways Q and R and the head J of the bolt is guided on the way S, so that as the bolt is withdrawn by the lock mechanism, the cam surfaces P force the bolt transversely and the locking projection L is released from 95 the inwardly projecting portion T of the lock strike. If, however, a thin flexible piece of material, as a piece of celluloid, is attempted to be thrust around the molding U and between the door and door jamb in 100 front of the strike, the pressure of the end of said flexible material against the beveled face K of the bolt merely tends to force the projection L against the inwardly projecting portion T of the strike.

In Figs. 4, 5 and 6, a modification of the invention is shown, in which the beveled head V of the bolt is provided with the projection W, but the cam surfaces P are omitted and in order to guide the bolt in the 110

lock casing, a beveled projection or cam surface X is provided in addition to the ways Q, R and S, so that as the bolt is withdrawn by the lock mechanism, the bolt is moved transversely to release the locking projection W from the strike D'. Any attempt, however, to force the bolt longitudinally by means of a piece of flexible material inserted between the door and the jamb 5 simply forces the locking projection W against the strike D'. Both constructions shown in the drawings operate efficiently and well and effectually prevent the forcing of the lock under the conditions described. 10

15 We claim and desire to obtain by Letters Patent the following:

1. In a spring-latch lock, the combination of a lock casing and a lock strike, a bolt in the lock casing having a beveled end provided with a safety projection forming a continuation of the beveled face of the end, the slope of the back of the said safety projection being substantially equal to the slope of the said beveled face of the end of the bolt, said safety projection freely entering the cavity of the lock strike, and guideways in the lock casing for guiding the bolt 20 as it is withdrawn with sliding and transverse movement to release said projection 25 from the strike, whereby forcing of the bolt 30

by the insertion of a piece of thin flexible material between the door and door jamb is prevented by the said safety projection.

2. In a spring-latch lock, the combination of a lock casing adapted to be secured to the door, and a lock strike having an undercut cavity in the door jamb, a bolt slidable in the lock casing and provided with a beveled end having a projection forming a safety catch or toe as a continuation of the beveled face of the bolt, the slope of the back of the said safety projection being substantially equal to the slope of the said beveled face of the end of the bolt, and guideways in the lock casing for moving the bolt transversely as it is drawn inwardly, to release the safety catch from the strike, whereby the forcing of the bolt by the insertion of a piece of thin flexible material between the door and door jamb is prevented by the said 40 safety projection. 45

In testimony whereof we have signed this specification in the presence of two subscribing witnesses.

JOHN WINN.
AARON FEINBERG.
